MACHINE FOR FORMING SEWER-PIPE OF CONCRETE.

1,177,732.

Specification of Letters Patent.

Patented Apr. 4, 1916.

Application filed February 7, 1914. Serial No. 817,208.

To all whom it may concern:

Be it known that we, JOHN H. STEWART and JOHN M. SCHENK, citizens of the United States of America, and residents of Waterloo, Blackhawk county, Iowa, have invented certain new and useful Improvements in Machines for Forming Sewer-Pipe of Concrete, of which the following is a specification.

10 Our invention relates to improvements in sewer-pipe machines, and the object of our improvement in such machines is to furnish means for forming the hollow sewer-pipe from concrete or similar materials adapted 15 to also form a bell or expansion at one end of each pipe. This object we have accomplished by the mechanism which is herein-after described and claimed, and which is 20 illustrated in the accompanying drawings, in which:

Figure 1 is a side elevation of our improved pipe machine. Fig. 2 is a front elevation of said machine. Fig. 3 is an enlarged horizontal section of the parts of 25 said machine, shown in Fig. 4, taken on the line *a*—*b* of the latter. Fig. 4 is a vertical axial section of a hollow mold-casing, a pipe being formed therein, and the former-head of the machine operatively located within 30 said parts, and in a position suitable to form the expanded or bell-shaped end of the said pipe.

Similar numerals of reference denote corresponding parts throughout the several 35 views.

Hitherto, in the making of hollow sewer-pipes from concrete or the like materials by forming mechanism, it has been found difficult, if not impossible, to properly form on 40 one end of such pipe, a bell or hollow expansion of the kind necessary for use in fitting such pipes together for use as sewer-pipe, especially. The mechanism shown, described and claimed herein, is intended to 45 furnish the necessary means for the end described.

Referring first to Fig. 4, a hollow, cylindrical mold-casing 11 is shown in longitudinal axial section, and has one end expanded 50 in diameter at 12, with an annular cap 9 fitted over said lower expanded end 12. A cylindrical former-head 1 is shown fitting the concentric central opening of said cover 9, the diameter of said former-head being 55 that of the interior hollow of a pipe, to be

formed within said mold-casing. Said former-head 1 is secured coaxially and upon the lower end of a vertical rotatable shaft 14. The numeral 2 denotes an abutment fixed on the top of the former-head being centrally orificed to permit the passage of the shaft 14 therethrough. The ends of this body are curved, and extend only as far outwardly as the circumferential periphery of said former-head. Crescent shaped rubber blocks 10 are mounted on the convex faces of the bodies 2 for adjustment outwardly to take up for wear thereon, and are adapted to trowel the cement upon the inner wall of the mold-casing 11. The numeral 3 denotes lugs projecting oppositely from opposite sides of said packer-body 2—10, and orificed horizontally and transversely to receive the pintles 4, on which are pivotally mounted the forked parts of the swinging former-bodies 5. These bodies are each formed with a relatively wider loop 7 at their outer ends, curved preferably on an arc of the cylindrical inner wall of the pipe. These loops are somewhat inclined forwardly and downwardly for a purpose to be hereinafter described. We have provided means for swinging said parts 5—7 up or down on their pintles 4, as follows: The numeral 6 denotes a block mounted movably between the forks of the part 5 near its loop 7, and having pintles extending movably into orificed seats in said forks. The numeral 8 denotes a rod, whose lower end is secured to the block 6, while its upper end is secured to a lug on one side of a collar 17 slidably mounted upon said rotatable shaft 14. The numeral 55 denotes a pair of bars spaced apart and located on opposite sides of the shaft 14, whose spacing bolts serve as seats for said rods 8. A hand lever 20 is medially pivoted to a fixed bracket or support 21, fixedly mounted on the cross-bar 24, the latter fixedly connected to the sleeve 18, and is also pivotally connected to the upper part 17 of the slidable collar 16. Said lever 20 is employed, together with its said connections, to swing up or down the bodies 5 by means of the rods 8, as indicated by both the full lines and the dotted lines in Fig. 4. The mechanism of our machine is mounted in and supported by the two front uprights 45 and the two rear uprights 50, which are connected by means of different horizontal 105 110

beams, such as 49 and 51 on the sides, and 33, 32, 30 and 24 in front. Said uprights are fixedly supported upon base beams 75, and a rotary horizontal carriage 74 is mounted in front of the two front uprights 45, and adapted to receive the base supporting ring 9 of the mold-casing 11.

A shaft 14 is rotatably and slidably mounted in alined bearings on the cross-beams 32 and 33. The belt-wheel 34 is splined upon the other end of the shaft 14 between the cross-beams 32 and 33 to rotate same by permitting the shaft to slide through its hub vertically. Said belt-wheel 15 34 is driven to rotate said shaft by means of the belt 35, which is carried over the idler-pulley 46, whose pintles 47 are mounted in bearings 48 on the upper side of the cross-beams 49. From thence, the said belt is carried downwardly and passed about the driving pulley 63, the latter being mounted upon a horizontal shaft 59, and the latter being rotated by any suitable prime-motor. The said shaft is raised and lowered by means of 20 the following described mechanism: The numeral 54 denotes a cable, one end of which is secured to the collar 27 fixed on said shaft 14. It is then carried about an idler-pulley 62, mounted in said frame and carried thence 25 downwardly and passed about and secured to a winding-drum 43, whose shaft 42 is rotatably mounted in bearings 52 on the side cross-beams 51. Mounted on the same shaft is a worm-wheel 41, which is in mesh with 30 a worm 40 on the horizontal shaft 37, the latter rotatably mounted in bearings 36 on the cross-beam 30, and the similar cross-beam connecting the rear uprights 50 of the machine. Mounted loosely, but non-slid- 35 ably, upon said shaft 37 are the belt-wheels 38 and 70, provided with oppositely-directed like friction-rims 65 and 69, containing annular friction-heads 66. The numeral 67 denotes a cylindrical body mounted slidably 40 upon said shaft 37, and having oppositely coned ends which are adapted to enter alternately and fit the inner faces of said friction-head 66, to alternately push said heads into frictional driving engagement with the 45 friction-rims 65 and 69, respectively. Said body 67 is moved along the shaft 37 by means of an arm 68 pivoted medially thereto, the arm 68 forming one member of the bell-crank lever 53, which is fulcrumed upon 50 a short shaft seated in a bearing 71 on the under side of one of the side cross-beams 51. The other arm or member of said bell-crank lever 53 is extended forwardly and pivotally connected to a vertical rod 29, the latter being movably seated in bearing orifices in the brackets 72 and 73, supported on a front upright 45. Near the upper and lower ends of said rod 29 are fixed thereon the collars 31 and 28, respectively. Said collars limit the 55 up and down movement of said rod by re-

spectively engaging the said brackets 72 and 73 when at the upper or lower limits of movement. One of the sleeves 22 on the cross-bar 24, and which is slidably mounted on one of the rods 81, has a rearwardly projecting lug 76, which, when the shaft 14 is moved up by reason of the winding up of the cable 54, comes into contact with the upper collar 31, and lifts it and said rod 29 upwardly until said collar engages the bracket 72. In lifting 75 the rod 29 upwardly, the bell-crank lever 53 is lifted, causing its arm 68 to shift the cylindrical body 67 out of engagement with the friction clutch 66, and into engagement with the other friction clutch 69. Upon the shaft 80 59 are fixedly mounted the two pulleys 44 and 60, driving respectively the belts 39 and 61, which in turn, drive the pulleys 38 and 70 on the shaft 37. Since both of the pulleys 38 and 70 are loose upon the shaft 37, except 85 when temporarily connected thereto by means of one or the other of said friction-clutches, the result of the preceding action is to reverse the direction of rotation of the shaft 37, its worm 40, the worm-wheel 41 90 and the winding-drum 43, which causes an unwinding of the cable 54, permitting said shaft 14 to descend under the action of gravity to its lowermost position. As the shaft 14 approaches the lower limit of its descending movement, the lug 76 of said sleeve 22 engages the lower collar 28 and pulls down the rod 29 until said bell-crank lever 53 causes the arm 68 to move the body 67 out of engagement of the clutch 69 and into engagement with the clutch 65. In this way, the shaft 37 has its rotation again reversed to wind up the cable 54 and again lift the shaft 14.

The numeral 56 denotes a hand-lever pivoted at its lower end to one of the uprights 45, and has a connecting-rod 57 pivotally connected thereto, the other end of said rod 57 being slidable in a bearing 64 on one of the rear uprights 50. Other connecting rods 58 are pivotally connected between the rod 57 and the horizontal arm of the bell-crank lever 53. When it is desired to reverse the direction of rotation of the shaft 37 at any stage of its movement, said hand-lever 56 115 may be shifted appropriately to move said parts to act upon the body 67 to engage either of the friction clutches.

The hinged forming-bodies 7 on the former-head 1 are raised and lowered as follows: The sleeve 17 which is fixedly connected to the other sleeve 16 is slidable upon said shaft 14. The spaced vertical rods 81 are supported in bearings 23 on the cross-bar 25, also in bearings on the cross-bars 32 120 and 33. The numeral 26 denotes an annular table with a raised rim, seated concentrically about the shaft 14, and having on opposite sides, bearings which are slidably seated upon said rods 81. Rods 77 have their lower 125

- ends secured to the bearings on said table 26 and extend upwardly to have their upper ends slidably seated in orificed lugs 80 on the cross-bar 32. The numerals 79 and 78 5 note spaced collars secured on said rods 77 on opposite sides of the lugs 80. The bearings 22 are adapted to come into contact with the lowermost collars 78 when they have moved upwardly toward the upper- 10 most limit of their vertical movement, carrying said collars upwardly with them, thus lifting the table 26. When said table 26 is thus lifted, a hollow cylindrical mold-casing 11, such as is shown in Fig. 4, may be seated 15 upon the carriage 74 concentric with and under the raised former-head 1. As the vertical movement of the shaft 14 is reversed, and said shaft descends, the bearings 22 follow, and the table 26 descends until it 20 rests upon the top of the collar-casing 11, concentrically, with its central opening coincident with the opening of the upper end of the mold-casing. The shaft 14 continues to descend, clearing the former-head 1 down to 25 the bottom of said mold-casing, as indicated in said Fig. 4, without affecting the table 26, which remains in its said position. The collars 79 on the rods 77 hold said table from descending when it has dropped to a 30 certain limit.
- Semi-fluid concrete may be deposited upon the table 26 to pass through its central opening into the hollow of the mold-casing 11. The shaft 14 then being put into rotation, 35 and the former-bodies 7 being lowered by depressing the hand-lever 20, the said bodies 7, in rotating, while the former-body 1 is rotating but not lifting, move within the bell 12 of said casing and the hollow of the pallet 9 to trowel the bell-shaped end of the tile 13 therein. When said bell-shaped end 40 is formed by the packing action of the bodies 7, the material crowded under the bodies 7 by the other packer-bodies 2—10 lifts them gradually to swing them to their 45 raised positions, and then the lever 20 is sprung to one side enough to engage the hanger-bracket 82, which holds it until released to permit it to descend. The former- 50 head 1, which is still in rotation, is then started on its upper movement by using the starting-lever 56. The cylindrical part 1 then trowels the cylindrical part of the tile in its upward movement through the casing
11. As the former-head arrives in its upper 55 position clearing the top of said casing 11, the table 26 is lifted by means of the above described mechanism, releasing the casing 11, which may then be swung out of line with said former-head by rotation of the 60 carriage 74. The mold-casing with the formed tile 13 may then be removed, and the casing taken off.
- The former-body 7 is somewhat inclined so as to coöperate with the curved packer- 65 bodies 2 in acting upon the concrete to engage the same and both trowel and pack it into place against the inner wall of the mold-casing.
- It is obvious that the former-head 7 may 70 be differently shaped and variously supported and actuated, as desired, to form the bell-shaped end of the tile 13 in coöperation with the former-head 1, without departing from the scope and principles of our invention. Also other equivalent mechanisms 75 may be used as found convenient to raise and lower said head, and simultaneously rotate the same. We do not wish to be understood to be confined specifically to the mech- 80 anism shown for that purpose.
- Having described our invention, what we claim as new, and desire to secure by Letters Patent, is:
- In combination, in a machine for forming 85 bell-end sewer pipe sections, a mold-casing having a bell-end, an annular pallet for partially closing said bell-end, a rotatable cylindrical former-head movable axially longitudinally through the mold-casing, an 90 arm pivoted to the top of said former-head and having its outer end bent downward obliquely, a rod having its lower end pivoted to said arm intermediate the ends of the latter, means for raising and lowering 95 said rod to swing the downwardly bent end of the arm beyond the former-head into the bell-end of the mold-casing over said pallet, and means for simultaneously rotating said former-head and moving it longitudinally 100 through the mold-casing.

Signed at Waterloo, Iowa, this 21st day of Jan. 1914.

JOHN H. STEWART.
JOHN M. SCHENK.
